UNITED STATES PATENT OFFICE

133,180

DESIGN FOR A DOLL

Marion Hoyle, San Francisco, Calif.

Application November 29, 1941, Serial No. 104,400

Term of patent 3½ years

To all whom it may concern:

Be it known that I, Marion Hoyle, a citizen of the United States, residing at the city and county of San Francisco, State of California, have invented a new, original, and ornamental Design for a Doll, of which the following is a specification, reference being had to the accompanying drawing, forming part thereof.

Fig. I, is a front elevational view of a doll showing my new design.

Fig. II, is a rear elevational view and

Fig. III, is a side elevational view of the same.

I claim:

The ornamental design for a doll, as shown.

MARION HOYLE.
